UNITED STATES PATENT OFFICE.

ANDREW F. FORD, OF SPOKANE, WASHINGTON.

GEARLESS DIFFERENTIAL.

1,365,586.

Specification of Letters Patent. Patented Jan. 11, 1921.

Application filed June 8, 1920. Serial No. 387,340.

To all whom it may concern:

Be it known that I, ANDREW F. FORD, a citizen of the United States, residing at Spokane, in the county of Spokane and State of Washington, have invented certain new and useful Improvements in Gearless Differentials, of which the following is a specification.

This invention relates to differentiating mechanism and refers to that class of machinery having for its object to provide a means whereby different requirements of speed and power may be obtained.

One object of my invention is to provide a means that will communicate equal power to both sides of the differential.

A further object is to provide a differential that will provide power to both sides at once and that while one side may "crawl," the lagging side will maintain its motion as it receives the full power.

A further object is to provide a differential having no gears.

A further object is to provide a differential that is simple to construct and that is relatively cheap to manufacture due to all machine work being truly circular.

With these and other objects in view, reference is now had to the accompanying drawings in which—

Figure 1 is a plan view of the device partly in section;

Fig. 2 is a side elevation with one end removed;

Fig. 3 is a sectional view of the cup shaped driven member;

Fig. 4 is a sectional view of the cylindrical tubular driving member;

Fig. 5 is a side elevation of the cylindrical driving member;

Fig. 6 is an end view of a wedge block;

Fig. 7 is an end elevation of the cylindrical driven member;

Fig. 8 is an end elevation of the cup shaped driven member.

Fig. 9 is a plan view of the parts assembled, showing wedge blocks in racing position.

Fig. 10 is a similar view, but with wedge block gripping.

Fig. 11 is another view with the wedge blocks in another gripping position; and

Fig. 12 is another similar view with the wedge blocks in another gripping position.

Having reference to the drawings, like numerals refer to like parts throughout and the numeral 1 refers to the cup-shaped driven member which consists of a bore 2 which is truly cylindrical and positioned eccentrically in the member throughout approximately one-half its length. A second bore 3 is also positioned eccentrically therein but diametrically opposite the first mentioned bore, (as plainly shown in Fig. 3), and between these bores is a guide portion 4 which separates or divides the bores and acts as a bearing for the cylindrical tubular driving member 5.

The diameter of the bores are preferably alike and the diameter of the guide portion 70 is obviously smaller as it unites with the sides of least eccentricity of both the bores.

In the cup shaped driven member is shown a bearing stud 6 which may be used if desired to support one end of the cylindrical 75 driven member 7, and integral with this cup shaped driven member is shown a portion of a shaft 8 which represents a power transmitting means.

It will be understood that this means may 80 be removably mounted in the member without departing from the spirit of my invention.

The cylindrical tubular driving member 5 consists of the tube as shown in Fig. 4 and 85 has attached thereto a driving means such as shown at 9 which represents a gear in this case.

Movably mounted in the walls of this cylinder and on quarters are wedge blocks 90 10, 11 and 12 respectively, the movement and position of which will be presently explained.

This driving member 5 is revolvably mounted in the cup shaped driven member 95 1 and is maintained in a central position therein by the guide portion 4 which also acts as a bearing point therefor.

The cylindrical driven member 7 is eccentrically mounted in the driving member 100 5, the eccentricity being maintained by the guide portion 13 which is concentric with the shaft 14 and the inner perimeter of the member 5. This shaft also representing a

power transmitting means. In the opposite end of this driven member is provided a journal 15 which registers with the bearing stud 6.

5 With the parts shown in Figs. 3, 4 and 5 assembled they would form a view similar to that shown in section in Fig. 1 in which the side of greatest eccentricity of the cylindrical driven member 7 is in contact with the inner portion of the wedge block 12, while its opposite side is in contact with the block 11; the blocks are shortened slightly to give a small amount of play between the parts.

10 15 As the driving member is rotated the blocks are carried with it until the back lash is taken up and the blocks bind between the driven members which will then rotate with the driving member.

20 25 By referring to the Figs. 9, 10, 11 and 12, in which the various positions are shown, it may be seen that a slight movement of a driven member will change the position of the wedge blocks until they wedge between the two driven members carrying them along with the driving member; the slight movement being sufficient to change the concentricity of the members 1 and 7.

30 35 In Fig. 9 I show the parts assembled, in plan, with the wedge blocks 10 in what is termed a racing position, *i. e.*, with the members 1 and 7 concentrically positioned so that the wedge blocks are free to move in the race formed by these members. In this position there is no gripping effect in the bore 2, but there now occurs a gripping in the bore 3, see Fig. 11, as note the block 12 therein. In this view a slight movement to the left of the members 1 and 5 has occurred, which 40 has changed the concentricity. This view also shows the slight movement required to engage the blocks, the amount of movement of the parts 5 and 1 with relation to the part 7 being indicated by the lines thereon; and 45 in this respect it must be noted that this movement (back lash) is exaggerated as the blocks are purposely shortened to clearly show a clearance between the blocks and the bores.

50 55 In Fig. 10 it will be plainly noted that the parts are locked against either forward or backward movement, the forward movement and the back lash being clearly demonstrated in Fig. 12.

60 65 It is obvious that the eccentrically positioned bores in the cup shaped driven member may have a common center, provided the cylindrical driven member is constructed with its eccentricity positioned on diametrically opposite sides, thus showing that the order of construction may be reversed.

It is also obvious that a greater number of bores may be used if desired.

This application is an improvement over

my former patent No. 1336950 and dated 65 April 13, 1920.

Having thus described my invention, I claim:

1. In a differential, a cup shaped driven member formed by a plurality of cylindrical bores eccentrically positioned therein, and a guide portion centrally positioned and dividing said bores, and carrying an internal bearing stud therein, a cylindrical driving member revolvably mounted in said cup shaped driven member and maintained centrally by said guide portion, and containing movably mounted wedge blocks, a cylindrical driven member eccentrically mounted in said driving member, to register operatively 70 with said wedge blocks and carrying a concentric guide portion, and carrying a journal to register with said bearing stud, and a power transmitting means attached to said driven members.

2. In a differential, a cup shaped driven member formed by a plurality of cylindrical bores eccentrically positioned and centered diametrically opposite each other, and a concentric guide portion dividing said bores, a 75 cylindrical tubular driving member revolvably mounted in said cup shaped driven member and maintained centrally therein by means of said guide portion, and containing movably mounted wedge blocks, a cylindrical driven member eccentrically mounted in said driving member, to register operatively 80 with said wedge blocks, and carrying a concentric guide portion to maintain the eccentricity of said cylindrical driven member in 85 said driving member, and a power transmitting means attached to said driven members.

3. In a differential, a cup shaped driven member formed by a plurality of bores, of equal diameters, eccentrically positioned and 90 centered diametrically opposite each other, a cylindrical tubular driving member revolvably mounted and centrally positioned in said cup shaped driven member, and containing a plurality of movably mounted 95 wedge blocks positioned on quarters within the wall thereof, said blocks being positioned to register operatively with the aforementioned bores, a cylindrical driven member eccentrically mounted in said driving member to register operatively 100 with said wedge blocks, and carrying a concentric guide portion to maintain the eccentricity of said cylindrical driven member in said driving member, and a power transmitting means 105 attached to said driven members.

4. In a differential, a cup shaped driven member formed by cylindrical bores of equal diameters and centered eccentrically and diametrically opposite each other therein, a 110 cylindrical tubular driving member revolvably mounted in said cup shaped driven member and maintained centrally therein,

and containing movably mounted wedge blocks, a cylindrical driven member eccentrically mounted in said driving member and carrying a concentric guide portion, and 5 power transmitting means attached to said driven members.

5. In a differential, a cup shaped driven member having eccentric inner walls, a cylindrical, tubular, driving member revolubly

mounted in said cup shaped driven member 10 and containing movably mounted wedge blocks, a cylindrical driven member eccentrically mounted in said driving member, and power transmitting means attached to said driven members. 15

In testimony whereof I affix my signature.

ANDREW F. FORD.
